CLAIM

The ornamental design for a compact portable kitchen, as shown and described.

DESCRIPTION

[22] Filed: Nov. 21, 1985

FIG. 1 is a front and right side perspective view of a compact portable kitchen showing my new design; and FIG. 2 is a left side elevational view thereof. The undisclosed bottom of the deep fat fryer shown in FIG. 1 is understood to be conventional. The undisclosed rear is substantially flat and unornamented.
